US012369722B2

(12) **United States Patent**
Jewett et al.

(10) **Patent No.:** US 12,369,722 B2
(45) **Date of Patent:** Jul. 29, 2025

(54) **METHOD OF DISASSEMBLING POCKETED SPRING ASSEMBLY WITH DIMENSIONALLY STABILIZING SUBSTRATE**

(71) Applicant: **L&P Property Management Company**, South Gate, CA (US)

(72) Inventors: **Jason V. Jewett**, Carthage, MO (US); **Seth Thompson**, Carthage, MO (US); **Darrell Richmond**, Carthage, MO (US)

(73) Assignee: **L&P Property Management Company**, South Gate, CA (US)

(*) Notice: Subject to any disclaimer, the term of this patent is extended or adjusted under 35 U.S.C. 154(b) by 269 days.

(57) **ABSTRACT**

A pocketed spring assembly comprises a plurality of parallel strings of individually pocketed springs. A dimensionally stabilizing substrate is secured to at least some of the strings on one of the top and bottom surfaces of the strings. A scrim sheet is secured to at least some of the strings on an opposed surface of the strings to maintain the positions of the strings. The dimensionally stabilizing substrate is laterally rigid enough to maintain length and width dimensions of the coil spring assembly. However, the dimensionally stabilizing substrate is flexible enough to allow the pocketed spring assembly to be roll packed for shipping.

**METHOD OF DISASSEMBLING POCKETED
SPRING ASSEMBLY WITH
DIMENSIONALLY STABILIZING
SUBSTRATE**

**CROSS-REFERENCE TO RELATED
APPLICATIONS**

This application is a Continuation-In-Part of U.S. patent application Ser. No. 17/244,021 filed Apr. 29, 2021 (pending), which is a Divisional of U.S. patent application Ser. No. 15/987,185 filed May 23, 2018 (now U.S. Pat. No. 11,013,340 which issued May 25, 2021), the disclosures of which is incorporated by reference herein in their entirety.

FIELD OF THE INVENTION

This invention relates generally to bedding and seating products and, more particularly, to pocketed spring assemblies used in bedding and seating products.

BACKGROUND OF THE INVENTION

Mattress spring core construction over the years has been a continuously improving art with advancements in materials and machine technology. A well-known form of spring core construction is known as a Marshall spring construction wherein metal coil springs are encapsulated in individual pockets of fabric and formed as elongate or continuous strings of individually pocketed coil springs. Due to the fabric used in pocketed spring assemblies being weldable to itself, these strings of pocketed springs are manufactured by folding an elongate piece of fabric in half lengthwise to form two plies of fabric and thermally or ultrasonically welding transverse and longitudinal seams to join the plies of fabric to define pockets within which the springs are enveloped. One such fabric is a non-woven polypropylene fabric.

Once strings of pocketed springs are constructed, they may be assembled to form a pocketed spring assembly for a mattress, cushion, or the like by a variety of methods. For example, multiple or continuous strings may be arranged in a row pattern corresponding to the desired size and shape of a mattress or the like, and adjacent rows of strings may be interconnected by a variety of methods. The result is a unitary assembly of individually pocketed coil springs.

The pocketed spring assembly then must be shipped to a mattress or furniture manufacturer for further assembly. One method of shipping a plurality of pocketed spring assemblies is to roll pack them into a roll for shipping. Upon receipt, the mattress or furniture manufacturer unrolls the pocketed spring assemblies and secures cushioning layers to one or both the top and bottom of each pocketed spring assembly before covering the cushioned pocketed spring assembly to create a finished mattress or furniture cushion.

In order to assist a mattress or furniture manufacturer to handle one of the pocketed spring assemblies, top and bottom scrim sheets, made of non-woven polypropylene fabric, are secured to the top and bottom surfaces, respectively, of the pocketed spring assembly by the spring assembler before the spring assembler roll packs the pocketed spring assemblies for shipment to the mattress or furniture manufacturer. Therefore, the top and bottom scrim sheets must be bendable to allow the innerspring unit to be rolled up as is required in the packaging process ("roll packing") for shipment to the mattress manufacturer.

In the current environment in which finished mattresses commonly are ordered online, it is desirable for a finished

mattress to be capable of being rolled up for shipment. It is increasingly common for a finished mattress to be compressed and rolled so that it may fit into a parcel carrier-friendly sized box and delivered directly to the consumer. 5 Thus, a finished mattress must be able to bend in the Z axis direction.

The common non-woven polypropylene scrim sheets incorporated into a pocketed spring assembly today bend in the X and Y and Z axis directions, but lack the rigidity to 10 maintain the sizing of the pocketed spring assembly in the X and Y (length and width) axis directions after such pocketed spring assemblies are unrolled. Common non-woven polypropylene scrim sheets incorporated into pocketed spring assemblies help with the manual handling of the pocketed spring assembly during manufacturing of the pocketed spring assembly. They also help the mattress manufacturer upholster the pocketed spring assembly into a finished mattress.

However, upon being unrolled, a pocketed spring assembly 20 having conventional non-woven polypropylene scrim sheets is not always the correct size in the X and Y (length and width) axis directions needed by a mattress manufacturer to apply cushioning materials. Different pocketed spring assemblies coming out of the roll may be different sizes due to their different locations within a roll. The pocketed spring assemblies closer to the center of the roll are wound tighter than the pocketed spring assemblies around the outside of the roll. The unrolled pocketed spring assemblies may vary in size in the X and Y (length and width) axis 25 directions and behave like an accordion due to the stretching nature of the non-woven polypropylene scrim sheets connecting the pockets together. After being shipped to a mattress manufacturer after being in a rolled state for some time, the dimensions of the pocketed spring assembly may 30 change over time, which is undesirable for a mattress manufacturer.

Today it's necessary for a mattress manufacturer to apply a sheet of polyurethane foam (referred to as "base foam") to the bottom of the pocketed coil spring assembly to create the 40 necessary rigidity described above. A laborer must spray either water-based or hot-melt adhesive on the surface of the pocketed spring assembly and/or the polyurethane foam while the bottom of what will eventually become the mattress is facing upward. The foam is then applied, and the 45 laborer must push or pull the pocketed spring assembly to the dimensions of the foam. This "sizes" the pocketed spring assembly to the precise dimension necessary such as 60" x 80" for a typical United States "queen" size as defined the International Sleep Products Association (ISPA). This process is difficult as the laborer must balance the time needed to achieve an aesthetically pleasing result with the "tack" 50 time of the adhesive. If the laborer spends too much time trying to wrestle the pocketed spring assembly into place the adhesive will set up/cure and a poor bond will result, causing 55 lost time as the process must then restart from the beginning. Now, since it was necessary to turn the bottom of the pocketed spring assembly upward to apply the base foam, the operator must now flip the pocketed spring assembly top side up so that the remainder of the mattress upholstery layer 60 can be applied.

Pocketed spring assemblies can weigh as much as 100 pounds, so this task is challenging from an ergonomic perspective and creates the potential for an injury to the laborer. In some cases, it may even be necessary for the 65 mattress manufacturer to purchase and install expensive pneumatic devices to assist in the flipping of the pocketed spring assembly to avoid harm to the laborer.

The present invention solves these problems as a dimensionally stabilizing substrate is applied directly to the pocketed spring assembly at the time the pocketed spring assembly is manufactured. Thus, there's no need for the flipping of the mattress nor the time spent to apply adhesive for the base layer or time spent positioning the pocketed spring assembly to the dimensions of the base layer.

The method described above is a traditional and common method of upholstering an innerspring unit into a mattress. While this is widely practiced, there's a current trend toward utilizing a roll coating machine to assemble the mattress. A roll coating machine allows an operator to pass the pocketed spring assembly into an opening where the adhesive for the foam layers is applied evenly across the surface by a roller which is covered in water-based adhesive. After the pocketed spring assembly exits the opposite side of the roll coating machine a layer of foam is laid onto the surface of the pocketed spring assembly coated with adhesive. This method provides an even coat of adhesive to create a substantial bond. However, the pocketed spring assembly that is fed into the roll coating machine must be of a precise dimension in the length and width directions. This creates a challenge because, as mentioned herein, the pocketed spring assembly may not be stable in the length and width direction due to being roll packed.

Therefore, there is a need for a pocketed spring assembly which is rigid in the X and Y axis directions, but bendable in the Z axis direction for roll packing for shipment to a mattress manufacturer.

There remains a need to provide a pocketed spring assembly to a mattress manufacturer which does not have a base layer of foam.

There remains a need to provide a pocketed spring assembly to a mattress manufacturer which provides a more cost effect replacement for a base layer of foam.

SUMMARY OF THE INVENTION

In one aspect, a bedding or seating product comprises a pocketed spring assembly. The pocketed spring assembly comprising a plurality of parallel strings of springs joined together to form a pocketed spring assembly core. Each string is joined to at least one adjacent string. The strings of springs may extend longitudinally or transversely. Each string comprises a plurality of individually pocketed springs. Each string comprises a piece of fabric comprising first and second opposed plies of fabric on opposite sides of the springs and joined together along a longitudinal seam. A plurality of pockets is formed along the length of the string by transverse or separating seams joining the first and second plies, and at least one spring being positioned in each pocket.

A dimensionally stabilizing substrate is secured to one of top and bottom surfaces of at least some of the strings of the pocketed spring assembly core to create a pocketed core assembly. The dimensionally stabilizing substrate is laterally rigid enough to eliminate length and width elasticity of the coil spring assembly, yet remain flexible in the direction of a height of the pocketed spring assembly to allow the pocketed spring assembly to be roll packed. In one embodiment, the dimensionally stabilizing substrate is made from a continuous filament, needled polyester with a resin binder having a weight of at least two ounces per square yard.

Cushioning materials may be placed on one or both sides of the pocketed spring assembly, and an upholstered covering may encase the pocketed spring assembly and cushioning materials.

A flexible scrim sheet may be secured to at least some of the strings on a surface of the pocketed spring assembly core opposite the dimensionally stabilizing substrate. The flexible scrim sheet may be made of any material flexible in the X, Y and Z axis directions. The flexible scrim sheet may be made of non-woven polypropylene fabric or any other known materials. The dimensionally stabilizing substrate is thicker and more rigid than the scrim sheet. In some cases, the dimensionally stabilizing substrate is at least twice the thickness of the scrim sheet.

In another aspect, a pocketed spring assembly for a bedding or seating product comprises a pocketed spring assembly core, a dimensionally stabilizing substrate secured to at least a portion of the pocketed spring assembly core and a scrim sheet secured to at least a portion of the pocketed spring assembly core. The pocketed spring assembly core comprises a plurality of parallel strings of springs joined together. Each string is joined to an adjacent string. The strings may extend longitudinally from side-to-side or transversely from end-to-end or head-to-foot. Each of the strings comprises a plurality of interconnected pockets. Each of the pockets contains at least one spring encased in fabric. The fabric is joined to itself along a longitudinal seam and has first and second opposed plies of fabric on opposite sides of the springs. The fabric of the first and second plies is joined by transverse seams.

A dimensionally stabilizing substrate is secured to at least some of the strings. In most situations, the dimensionally stabilizing substrate is secured directly to at least some of the strings. The dimensionally stabilizing substrate is laterally rigid enough to eliminate length and width elasticity of the coil spring assembly yet remain flexible in the direction of the height of the pocketed spring assembly to allow the pocketed spring assembly to be roll packed.

A scrim sheet may be secured to one of the upper and lower surfaces of the strings of the pocketed spring assembly core to facilitate handling of the pocketed spring assembly.

In another aspect, a method of making a pocketed spring assembly for a bedding or seating product is provided. The method comprises joining a plurality of parallel strings of springs together to form a pocketed spring assembly core. The method further comprises gluing a dimensionally stabilizing substrate to at least some of the strings. The dimensionally stabilizing substrate is laterally rigid enough to eliminate length and width elasticity of the coil spring assembly yet remain flexible in the direction of the height of the pocketed spring assembly to allow the pocketed spring assembly to be roll packed. The method further comprises gluing a scrim sheet to at least some of the strings. The final method step comprises roll packing the pocketed spring assembly having a pocketed spring assembly core, one scrim sheet and one dimensionally stabilizing substrate secured to the pocketed spring assembly core.

In another aspect, a method of making a pocketed spring assembly comprises joining a plurality of parallel strings of springs together to form a pocketed spring assembly core. The method further comprises gluing a dimensionally stabilizing substrate to at least some of the strings. The dimensionally stabilizing substrate is laterally rigid enough to eliminate length and width elasticity of the coil spring assembly yet remain flexible in the direction of the height of the pocketed spring assembly to allow the pocketed spring assembly to be roll packed. The method further comprises gluing a scrim sheet to at least some of the strings. The final method step comprises roll packing the pocketed spring assembly having a pocketed spring assembly core, one scrim

sheet and one dimensionally stabilizing substrate secured to the pocketed spring assembly core.

In another aspect, a method of disassembling a pocketed spring assembly comprises providing a pocketed spring assembly having a dimensionally stabilizing substrate secured to one of top and bottom surfaces of the pocketed spring assembly and a scrim sheet secured to the other of the top and bottom surfaces of the pocketed spring assembly. The pocketed spring assembly comprises a plurality of parallel strings of springs joined together, each of the strings comprising a plurality of individually pocketed springs. Each of the strings comprises a piece of fabric joined along a longitudinal seam, first and second opposed plies of fabric being on opposite sides of the springs, a plurality of pockets being formed along a length of the string by transverse seams joining said first and second plies, and at least one spring being positioned in each said pockets. The dimensionally stabilizing substrate is thicker than the scrim sheet and more rigid than the scrim sheet.

The method comprises pulling the dimensionally stabilizing substrate and the scrim sheet away from each other to tear the strings along perforations in the piece of fabric. The perforations may surround each of the strings to create loops of perforations. After the fabric of the pocketed spring assembly is fully torn along either one set of loops of perforations or two sets of loops of perforations, the metal springs may be separated from the fabric for recycling purposes. Regardless of the number or pattern of perforations, the method comprises tearing each of the strings along perforations in the pieces of fabric of the strings to separate the metal springs from the fabric for recycling purposes.

In order to facilitate the tearing of the fabric along the perforation loop/loops in the strings, the transverse seams in the strings may either be interrupted or shorted to avoid any intersection of a loop of perforations with a transverse seam. In one embodiment in which each string only has one loop of perforations, the loop of perforations is typically closer to the dimensionally stabilizing substrate and the scrim sheet to facilitate a person or machine tearing along the perforations because the dimensionally stabilizing substrate is thicker and more rigid than the scrim sheet and thus easier to grab and control.

Another method of disassembling a pocketed spring assembly comprises providing a pocketed spring assembly having a dimensionally stabilizing substrate secured to one of top and bottom surfaces of the pocketed spring assembly and a scrim sheet secured to the other of the top and bottom surfaces of the pocketed spring assembly. The pocketed spring assembly comprises a plurality of parallel strings of springs joined together, each of the strings comprising a plurality of individually pocketed springs. Each of the strings comprises a piece of fabric joined along a longitudinal seam, first and second opposed plies of fabric being on opposite sides of the springs, a plurality of pockets being formed along a length of the string by transverse seams joining said first and second plies, and at least one spring being positioned in each said pockets. The dimensionally stabilizing substrate is thicker than the scrim sheet and more rigid than the scrim sheet.

The method further comprises grasping the dimensionally stabilizing substrate with one hand and the scrim sheet with the other hand and pulling an operator's hands apart. This movement tears each of the strings along the perforations in the piece of fabric of each string to separate the springs from the fabric. The dimensionally stabilizing substrate is easier to grasp than the scrim sheet because it is thicker than the scrim sheet. The dimensionally stabilizing substrate is rect-

angular and extends outwardly from the strings thus providing a handle which is easy for an operator to grab or grasp. The same is true of the scrim sheet.

The accompanying drawings, which are incorporated in and constitute a part of this specification, illustrate embodiments of the invention and, together with the summary of the invention given above, and the detailed description of the drawings given below, explain the principles of the present invention.

10

BRIEF DESCRIPTION OF THE DRAWINGS

FIG. 1 is a perspective view, partially broken away, of a bedding or seating product incorporating a pocketed spring assembly according to the principles of the present invention.

FIG. 2 is a perspective view, partially broken away, of the pocketed spring assembly of the mattress of FIG. 1.

FIG. 3 is a perspective view, partially broken away, of a bedding or seating product incorporating another pocketed spring assembly according to the principles of the present invention.

FIG. 4 is a cross-sectional view, partially broken away, taken along the line 4-4 of FIG. 2.

FIG. 4A is a cross-sectional view, partially broken away, taken along the line 4A-4A of FIG. 2.

FIG. 5A is a perspective view of a dimensionally stabilizing substrate being compressed in the direction of the Y-axis.

FIG. 5B is a perspective view of a dimensionally stabilizing substrate being compressed in the direction of the X-axis.

FIG. 6A is a perspective view of a scrim sheet being compressed in the direction of the Y-axis.

FIG. 6B is a perspective view of a scrim sheet being compressed in the direction of the X-axis.

FIG. 7 is a side elevational view of a method of making a pocketed spring assembly in accordance with the present invention.

FIG. 8 is side elevational view of a method of roll packing multiple pocketed spring assemblies in accordance with the present invention.

FIG. 9 is a chart of data from a first test comparing a standard pocketed spring assembly having two scrim sheets to a pocketed spring assembly having one scrim sheet and one a dimensionally stabilizing substrate.

FIG. 9A is a perspective view of a person measuring a queen size pocketed spring assembly which resulted in the data shown in FIG. 9.

FIG. 10 is a graph of data from another test comparing a standard pocketed spring assembly having two scrim sheets to a pocketed spring assembly having one scrim sheet and one a dimensionally stabilizing substrate.

FIG. 11 is a chart of data from another test comparing a standard pocketed spring assembly having two scrim sheets to a pocketed spring assembly having one scrim sheet and one a dimensionally stabilizing substrate.

FIG. 11A is a perspective view illustrating how the data shown in FIG. 11 was obtained.

FIG. 12 is a chart of data from another test comparing a standard pocketed spring assembly having two scrim sheets to a pocketed spring assembly having one scrim sheet and one a dimensionally stabilizing substrate.

FIG. 12A is a perspective view illustrating how the data shown in FIG. 12 was obtained.

FIG. 13 is a perspective view of the pocketed spring assembly of FIGS. 14A and 14B being flipped so the

dimensionally stabilizing substrate is on top and being torn apart to separate the springs from the fabric.

FIG. 14A is a side view of the pocketed spring assembly of FIG. 13.

FIG. 14B is an end view of the pocketed spring assembly of FIG. 13.

FIG. 14C is a side view partially in cross-section of the pocketed spring assembly of FIGS. 14A and 14B being torn apart to separate the springs from the fabric.

FIG. 15 is a perspective view of the pocketed spring assembly of FIGS. 15A and 15B.

FIG. 15A is a side view of an alternative embodiment of pocketed spring assembly having two sets of perforations.

FIG. 15B is an end view of an alternative embodiment of pocketed spring assembly having two sets of perforations.

FIG. 15C is a side view partially in cross-section of the pocketed spring assembly of FIG. 15A being torn apart to separate the springs from the fabric.

FIG. 16A is an enlarged view of one version of transverse seams which may be used in any of the embodiments shown or described herein.

FIG. 16B is an enlarged view of another version of transverse seams which may be used in any of the embodiments shown or described herein.

DETAILED DESCRIPTION OF THE INVENTION

Referring to FIG. 1, there is illustrated a bedding product in the form of a double-sided mattress 10 incorporating the principles of the present invention. This product or mattress 10 comprises a pocketed spring assembly 12 over the top of which lays conventional padding or cushioning layers 14, 16 which may be foam, fiber, gel, a pocketed spring blanket or any other suitable materials or any combination thereof. Similarly, conventional padding or cushioning layers 14, 16 lie below the pocketed spring assembly 12. An upholstered cover 20 surrounds the pocketed spring assembly 12 and conventional padding or cushioning layers 14, 16.

If desired, any of the padding or cushioning layers may be omitted in any of the embodiments shown or described herein. The novel features reside in the pocketed spring assembly.

As shown in FIG. 1, fully assembled, the product 10 has a length "L" defined as the linear distance between opposed end surfaces 22 (only one being shown in FIG. 1). Similarly, the assembled product 10 has a width "W" defined as the linear distance between opposed side surfaces 24 (only one being shown in FIG. 1). In the product shown in FIG. 1, the length is illustrated as being greater than the width. However, it is within the scope of the present invention that the length and width may be identical, as in a square product.

As shown in FIGS. 1 and 2, pocketed spring assembly 12 comprises a pocketed spring assembly core 34, a scrim sheet 36 and a dimensionally stabilizing substrate 38. The pocketed spring assembly core 34 is manufactured from multiple strings 26 of pocketed springs 28 joined together in any known manner, such as by gluing for example. Although pocketed springs 28 are typically metal coil springs 18 (as shown in FIG. 4), the springs may be any resilient members including foam, for example. Although the strings 26 of pocketed springs 28 are commonly arranged in transversely extending rows 30 and longitudinally extending columns 32, as shown in FIGS. 1 and 2, they may be offset, as is known in the art. The present invention is not intended to limit the configuration or type of pocketed spring assembly core 34 to

those illustrated. FIG. 3 illustrates an alternative pocketed spring assembly core 34a, as one example.

As best shown in FIG. 2, each string 26 extends longitudinally or from head-to-foot along the full length of the pocketed spring assembly core 34. Although the strings 26 are illustrated as extending longitudinally or from head-to-foot in the pocketed spring assembly 12 of FIGS. 1 and 2, they may extend transversely or from side-to-side as is known in the art. In any of the embodiments shown or described herein, the strings may extend either longitudinally (from end-to-end) or transversely (from side-to-side).

As best shown in FIGS. 4 and 4A, each string 26 of pocketed spring assembly core 34 comprises a piece of fabric joined along a longitudinal seam 40 shown in FIG. 1, first and second opposed plies of fabric 42, 44 being on opposite sides of the springs 18, a plurality of pockets 46 being formed along a length of said string 26 by transverse seams 48 joining said first and second plies, at least one spring 18 being positioned in each pocket 46. Although one type of spring 18 is shown, any spring may be incorporated into any of the pockets 46.

As best shown in FIG. 4A, each string 26 of pocketed spring assembly core 34 has an upper surface 68 and a lower surface 70. As best shown in FIG. 4A, the upper surfaces 68 of the strings 26 of pocketed spring assembly core 34 are generally co-planar in an upper plane P1 and the lower surfaces 70 of the strings 26 of pocketed spring assembly core 34 are generally co-planar in a lower plane P2. The linear distance between upper and lower surfaces 68, 70 of the strings 26 of pocketed spring assembly core 34 is defined as the height "H" of the pocketed spring assembly core 34 because all the strings 26 are the same height.

As best shown in FIG. 4, scrim sheet 36 is secured to an upper surface 68 of at least some of the strings 26 of pocketed spring assembly core 34 with adhesive/glue. Similarly, dimensionally stabilizing substrate 38 is secured to the lower surface 70 of at least some of the strings 26 of pocketed spring assembly core 34 with adhesive. Although not shown, the dimensionally stabilizing substrate 38 may be secured to the upper surface 68 of at least some of the strings 26 of pocketed spring assembly core 34 with adhesive and the scrim sheet 36 secured to the lower surface 70 of at least some of the strings 26 of pocketed spring assembly core 34 with adhesive. In some applications, the scrim sheet may be omitted.

As best shown in FIG. 2, scrim sheet 36 has a length "L1" defined as the linear distance between opposed end edges 52 (only one being shown in FIG. 2). Similarly, the scrim sheet 36 has a width "W1" defined as the linear distance between opposed side edges 54. In the pocketed spring assembly 12 shown in FIG. 2, the length is illustrated as being greater than the width. However, it is within the scope of the present invention that the length and width may be identical, as in a square pocketed spring assembly. As shown in FIG. 4, the scrim sheet 36 has a thickness "T1" defined as the linear distance between opposed top and bottom surfaces 60, 62, respectively. In one embodiment, the thickness T1 of the scrim sheet 36 is 0.009 inches, but may be any desired thickness. Scrim sheet 36 is preferably made of a non-woven polypropylene fabric which is commonly the material from which the strings 26 of pocketed spring assembly core 34 are made.

As best shown in FIGS. 6A and 6B, scrim sheet 36 is elastic or flexible in the directions of the X axis, Y axis and Z axis. On the other hand, as best shown in FIGS. 6A and 6B, dimensionally stabilizing substrate 38 is elastic or flexible in the direction of the Z axis only.

Referring to FIG. 6A, when a compressive force is exerted on the scrim sheet 36 in the direction of the Y axis, as illustrated by the arrows in FIG. 6A, the scrim sheet 36 bunches upwardly and forms an irregular pattern. In other words, the scrim sheet 36 is easily shortened in the direction of the Y axis when subject to a compressive force in the direction of the Y axis.

Referring to FIG. 6B, when a compressive force is exerted on the scrim sheet 36 in the direction of the X axis, as illustrated by the arrows in FIG. 6B, the scrim sheet 36 bunches upwardly and forms an irregular pattern. In other words, the scrim sheet 36 is easily shortened in the direction of the X axis when subject to a compressive force in the direction of the X axis.

Similarly, as best shown in FIG. 2, dimensionally stabilizing substrate 38 has a length "L1" defined as the linear distance between opposed end edges 56. Similarly, the dimensionally stabilizing substrate 38 has a width "W1" defined as the linear distance between opposed side edges 58 (only one being shown in FIG. 2). In the pocketed spring assembly 12 shown in FIG. 2, the length is illustrated as being greater than the width. However, it is within the scope of the present invention that the length and width may be identical, as in a square pocketed spring assembly. As shown in FIG. 4, the dimensionally stabilizing substrate 38 has a thickness "T2" defined as the linear distance between opposed top and bottom surfaces 64, 66, respectively. In one embodiment, the thickness T2 of the dimensionally stabilizing substrate 38 is 0.032 inches, but may be any desired thickness.

Referring to FIG. 5A, when a compressive force is exerted on the dimensionally stabilizing substrate 38 in the direction of the Y axis, as illustrated by the arrows in FIG. 5A, the dimensionally stabilizing substrate 38 bows either upwardly as shown in solid lines or downwardly as shown in dashed lines in the direction of the Z axis. The dimensionally stabilizing substrate 38 does not bunch upwardly and form an irregular pattern as the scrim sheet 36 does when subjected to the same force as shown in FIG. 6A. In other words, the dimensionally stabilizing substrate 38 resists being shortened in the direction of the Y axis when subject to a compressive force in the direction of the Y axis.

Referring to FIG. 5B, when a compressive force is exerted on the dimensionally stabilizing substrate 38 in the direction of the X axis, as illustrated by the arrows in FIG. 5B, the dimensionally stabilizing substrate 38 bows either upwardly as shown in solid lines (or downwardly as shown in dashed lines) in the direction of the Z axis. The dimensionally stabilizing substrate 38 does not bunch upwardly and form an irregular pattern as the scrim sheet 36 does when subjected to the same force as shown in FIG. 6B. In other words, the dimensionally stabilizing substrate 38 resists being shortened in the direction of the X axis when subject to a compressive force in the direction of the X axis.

One material which has proven effective for the dimensionally stabilizing substrate 38 is a continuous filament, needled polyester with a resin binder with a weight of at least two ounces per square yard. The resin may be corn starch. A weight of at least 3.5 ounces per square yard has proven to perform well. This material may be purchased from Hanes Companies of Conover, North Carolina, a division of Leggett & Platt, Incorporated.

FIG. 3 illustrates an alternative pocketed spring assembly 12a having a different pocketed spring assembly core 34a. The pocketed spring assembly core 34a includes a border 50 made of pocketed coil springs 51 (only a portion being shown in FIG. 3). The border 50 surrounds a central portion

72 (only a portion being shown in FIG. 3) comprising strings 26 of individually pocketed springs 28, as described herein. The pocketed springs 51 of border 50 are narrower than the pocketed springs 28 of the central portion 72 of pocketed spring assembly core 34a. Although one type of border 50 is illustrated, the border may assume other forms or shapes of pocketed coil springs. Alternatively, the border 50 may be omitted in this embodiment or any embodiment described or shown herein.

10 Strings of pocketed springs 26 and any other strings of springs described or shown herein, may be connected in side-by-side relationship as, for example, by gluing the sides of the strings together in an assembly machine, to create an assembly or matrix of springs having multiple rows and 15 columns of pocketed springs bound together as by gluing, welding or any other conventional assembly process commonly used to create pocketed spring cores or assemblies.

FIGS. 7 and 8 illustrate a method of making the pocketed spring assembly in accordance with the present invention.

20 Referring to FIG. 7, in an assembler 74 strings 26 of individually pocketed springs 28 are glued together to form a continuous pocketed spring web 92. Nozzles 75 apply adhesive/glue 76 to top and bottom surfaces 78, 80 of the pocketed spring web 92 as the pocketed spring web 92 is 25 moving downstream (to the right in FIG. 7). A roll 82 comprising a web 84 of non-woven polypropylene fabric or scrim material is unwound and placed upon the top surface 78 of the pocketed spring web 92 as the pocketed spring web 92 is moving downstream (to the right in FIG. 7). Similarly, 30 a roll 86 comprising a web 88 of dimensionally stabilizing substrate material is unwound and placed upon the bottom surface 80 of the pocketed spring web 92 as the pocketed spring web 92 is moving downstream (to the right in FIG. 7). The combination of the web 84 of non-woven polypropylene 35 fabric or scrim material, the pocketed spring web 92 and the web 88 of dimensionally stabilizing substrate material secured together will be called a continuous finished web 94 for purposes of this document.

As shown in FIG. 7, blades 90 move to cut the continuous 40 finished web 94 to a desired size to form a pocketed spring assembly 96. Although two blades 90 are shown, any number of blades including only one blade may be used.

As shown in FIG. 8, pocketed spring assembly 96 is 45 moved further downstream between two conveyor belts 98 to compress the pocketed spring assembly 96 for roll packing. The compressed pocketed spring assembly 96 is moved further downstream as indicated by the arrow 99 shown in FIG. 8. A web 100 of packaging material stored on a roll 102 is laid on the compressed pocketed spring assembly 96 and then rolled around a tube 104 into a roll-pack 106 for shipment.

FIG. 9 illustrates the results of a test in which two queen size pocketed spring assemblies were compared. FIG. 9A 50 illustrates how the test was performed. One pocketed spring assembly labelled "Standard" had dimensions in the X and Y axis directions of 79 inches by 56 inches before two scrim sheets of non-woven polypropylene fabric having a density of one ounce per square yard were attached to the top and bottom surfaces, respectively, of the pocketed spring assembly. A second pocketed spring assembly labelled "Substrate" 55 had dimensions in the X and Y axis directions of 79 inches by 56 inches before one scrim sheet of non-woven polypropylene fabric having a density of one ounce per square yard was attached to one the top and bottom surfaces of the pocketed spring assembly and a dimensionally stabilizing substrate was attached to the other of the top and bottom surfaces of the pocketed spring assembly. Each unit was 60 65

placed in the same position shown in FIG. 9A with each spring axis being horizontally oriented and the scrim sheet(s) generally vertically oriented. The strings extending from head to foot extended generally vertically when the units were measured. The data shown in FIG. 9 shows the pocketed spring assembly with the dimensionally stabilizing substrate was taller compared to the "Standard" unit without any load applied. FIG. 9A shows a person 108 using a tape measure 110 to obtain the data shown in FIG. 9.

FIG. 10 illustrates the results a test in which two mini-samples of pocketed spring assemblies were compared, each mini-sample comprising six strings, each string having six pocketed coil springs. Each barrel-shaped coil spring was eight inches tall with five convolutions and a maximum diameter of 77 millimeters. The mini-sample labelled "Standard" had two scrim sheets of non-woven polypropylene fabric having a density of one ounce per square yard attached to the top and bottom surfaces, respectively, of the mini-sample. A mini-sample labelled "Substrate" had one scrim sheet of non-woven polypropylene fabric having a density of one ounce per square yard attached to one the top and bottom surfaces of the mini-sample and a dimensionally stabilizing substrate was attached to the other of the top and bottom surfaces of the mini-sample. The mini-samples were put into an Admet® model eXpert 2653 testing machine. The chart shown in FIG. 10 shows a greater force was required to deflect the "Substrate" mini-sample a predetermined distance.

FIG. 11 illustrates the results a test in which 12 inch by 4 inch pieces of material were pushed along a flat surface with incrementally increasing weights placed on one end of the piece of material. FIG. 11A illustrates how the test was performed. The weight 112 shown in FIG. 11A and listed in the chart of FIG. 11 is the weight at which the piece of material 114 shown in FIG. 11A buckled during the test. The piece of material labelled "Standard" was made of non-woven polypropylene fabric having a density of one ounce per square yard. The piece of material labelled "Substrate" was a dimensionally stabilizing substrate material having a density of four ounces per square yard. As the chart shows, much more weight was required to make the dimensionally stabilizing substrate material buckle.

FIG. 12 illustrates the results a test in which 12 inch by 4 inch pieces of material were compressed using an Admet® model eXpert 2653 testing machine having two clamps 118 shown in FIG. 12A. FIG. 12A illustrates how the test was performed. The force listed in the chart of FIG. 12 is the weight at which the piece of material 116 buckled during the test. The piece of material labelled "Standard" was made of non-woven polypropylene fabric having a density of one ounce per square yard. The piece of material labelled "Substrate" was a dimensionally stabilizing substrate material having a density of four ounces per square yard. As the chart shows, much more weight was required to make the dimensionally stabilizing substrate material buckle.

FIGS. 13, 14A, 14B and 14C illustrate an alternative pocketed spring assembly 12b. Although the pocketed spring assembly 12b is shown having a pocketed spring assembly core 34b without edge support, the features of this embodiment of pocketed spring assembly may be used with any pocketed spring assembly core shown or described herein or known in the industry such as those with edge support on only two sides or edge support around the perimeter of the pocketed spring assembly core.

As shown in FIGS. 13, 14A, 14B and 14C, pocketed spring assembly 12b comprises a pocketed spring assembly core 34b, a scrim sheet 36 as shown and described herein

and a dimensionally stabilizing substrate 38 as shown and described herein. The pocketed spring assembly core 34b is manufactured from multiple strings 26b of pocketed springs 28b joined together in any known manner, such as by gluing for example. Although pocketed springs 28b are typically metal coil springs 18 (as shown in FIGS. 14A and 14B), the springs may be any resilient members including foam, for example. Although one configuration of metal coil spring 18 is shown, any metal coil spring may be used; the drawings are not intended to be limiting. Although the strings 26b of pocketed springs 28b are commonly arranged in transversely extending rows 30 and longitudinally extending columns 32, as shown in FIG. 13, they may be offset, as is known in the art. The present invention is not intended to limit the configuration or type of pocketed spring assembly core 34b to those illustrated.

As best shown in FIG. 13, each string 26b extends longitudinally or from head-to-foot along the full length of the pocketed spring assembly core 34b. Although the strings 26b are illustrated as extending longitudinally or from head-to-foot in the pocketed spring assembly 12b, they may extend transversely or from side-to-side as is known in the art. In any of the embodiments shown or described herein, the strings may extend either longitudinally (from end-to-end) or transversely (from side-to-side).

FIG. 14A illustrates one of the strings 26b with the coil springs 18 shown in dashed lines. As best shown in FIGS. 13 and 14B, each string 26b of pocketed spring assembly core 34b comprises a piece of fabric joined along a longitudinal seam 40b shown in FIG. 13, first and second opposed plies of fabric 42b, 44b being on opposite sides of the springs 18, a plurality of pockets 46b being formed along a length of said string 26b by transverse seams 48b joining said first and second plies, at least one spring 18 being positioned in each pocket 46b. Although one type of spring 18 is shown, any spring may be incorporated into any of the pockets 46b.

As best shown in FIG. 14A, each pocket 46b of pocketed spring assembly core 34b has an upper surface 68b and a lower surface 70b. As best shown in FIG. 14A, the upper surfaces 68b of the pockets 46b of pocketed spring assembly core 34b are generally co-planar in an upper plane P1 and the lower surfaces 70b of the pockets 46b of pocketed spring assembly core 34b are generally co-planar in a lower plane P2. The linear distance between upper and lower surfaces 68b, 70b of the strings 26b of pocketed spring assembly core 34b is defined as the height "H" of the pocketed spring assembly core 34b because all the strings 26b are the same height.

As best shown in FIG. 14A, scrim sheet 36 is secured to an upper surface 68b of at least some of the strings 26b of pocketed spring assembly core 34b with beads 71 of adhesive/glue. Similarly, dimensionally stabilizing substrate 38 is secured to the lower surface 70b of at least some of the strings 26b of pocketed spring assembly core 34b with beads 73 of adhesive. Although not shown, the dimensionally stabilizing substrate 38 may be secured to the upper surface 68b of at least some of the strings 26b of pocketed spring assembly core 34b with adhesive and the scrim sheet 36 secured to the lower surface 70b of at least some of the strings 26b of pocketed spring assembly core 34b with adhesive. In some applications, the scrim sheet may be omitted.

Instead of beads, the adhesive securing the strings 26b of pocketed spring assembly core 34b to the scrim sheet 36 and to the dimensionally stabilizing substrate 38 may be lines or segments of glue.

13

As best shown in FIG. 14B, adjacent strings 26b are glued to each other with beads of adhesive 81. Instead of beads, the adhesive securing adjacent strings 26b of pocketed spring assembly core 34b may be lines or segments of glue. Although FIG. 14B shows three levels of glue beads 81, any number of levels of glue may be used to secure adjacent strings 26b together.

As best shown in FIGS. 14A and 14B, each string 26b has a continuous loop 85 of perforations 87 around the entire string. FIG. 14A shows one side section 89 of the loop 85 of perforations 87 extending through one of the plies 42, 44 of the piece of fabric used to create the string 26b. FIG. 14B shows one end section 91 of the loop 85 of perforations 87 extending through the piece of fabric used to create each string 26b. The continuous loop 85 of perforations 87 extends around the entire string 26b facilitating the tearing of the fabric as described herein.

The pocketed spring assembly 12b has one continuous loop 85 of perforations 87 proximate the dimensionally stabilizing substrate 38 in the lower third of the pocketed spring assembly 12b.

As best shown in FIG. 16A, each of the transverse seams 48b has a gap 93 between weld segments. The continuous loop 85 of perforations 87 extends through the gaps 93 in the transverse seams of a string 26b to facilitate tearing the fabric of the string 26b.

FIG. 16B illustrates an alternative version of transverse seam 48bb in which a lower end 95 of the transverse seam 48bb is above the continuous loop 85 of perforations 87. Thus, the transverse seam 48bb is shorter than the other transverse seams shown or described herein. No portion of the transverse seam is outside the continuous loop 85 of perforations 87. Although FIGS. 16A and 16B show portions of transverse seams proximate the dimensionally stabilizing substrate 38 in the lower third of the pocketed spring assembly 12b, the upper portions of the transverse seams may be interrupted by another line of perforations proximate the upper scrim sheet 36, as shown in the embodiment shown in FIGS. 15A and 15B.

As shown in FIG. 14C, the metal coil springs 18 may be separated from the fabric of the pocketed spring assembly 12b by a person or machine grabbing the dimensionally stabilizing substrate 38 outside the pocketed spring assembly 12b and pulling downwardly in the direction of arrow 101. The force created by the person or machine causes the strings 26b of pocketed spring assembly 12b to tear along the continuous loops 85 of perforations 87. After the pockets 46b of strings 26b have been opened by the tearing of the fabric, the coil springs 18 may be removed from inside the pockets 46b either by gravity or machine or manually. See arrow 103 of FIG. 14C.

Tearing is possible because the tensile strength of the pieces of fabric of the strings 26b is less than the tensile strength of the dimensionally stabilizing substrate 38. In some applications, the tensile strength of the dimensionally stabilizing substrate 38 is at least twice as great as the tensile strength of the pieces of fabric of the strings 26b.

After the metal coil springs 18 have been separated from the fabric by tearing along the perforations 87, the fabric of the pocketed spring assembly 12b is separated into a first or lower section of fabric 105 having the dimensionally stabilizing substrate 38 and a second or upper section of fabric 107 having the scrim sheet 36. Although the perforations 87 are shown in continuous loops 85 around the strings 26b, the perforations 87 may be arranged in other configurations around a string 26b. This is true for any of the embodiments shown or described herein.

14

FIGS. 15, 15A and 15B illustrate an alternative pocketed spring assembly 12c. Although the pocketed spring assembly 12c is shown having a pocketed spring assembly core 34c without edge support, the features of this embodiment of pocketed spring assembly may be used with any pocketed spring assembly core shown or described herein or known in the industry such as those with edge support on only two sides or around the entire perimeter of the pocketed spring assembly core.

As shown in FIGS. 15, 15A and 15B, pocketed spring assembly 12c comprises a pocketed spring assembly core 34c, a scrim sheet 36 as shown and described herein and a dimensionally stabilizing substrate 38 as shown and described herein. The pocketed spring assembly core 34c is manufactured from multiple strings 26c of pocketed springs 28c joined together in any known manner, such as by gluing for example. Although pocketed springs 28c typically contain metal coil springs 18 (as shown in FIGS. 15A and 15B), the springs may be any resilient members including foam, for example. Although one configuration of metal coil spring 18 is shown, any metal coil spring may be used; the drawings are not intended to be limiting. Although the strings 26c of pocketed springs 28c are commonly arranged in transversely extending rows 30 and longitudinally extending columns 32, as shown in FIG. 15, they may be offset, as is known in the art. The present invention is not intended to limit the configuration or type of pocketed spring assembly core 34c to that illustrated.

FIG. 15A illustrates one of the strings 26c with the coil springs 18. As best shown in FIGS. 15 and 15B, each string 26c of pocketed spring assembly core 34c comprises a piece of fabric joined along a longitudinal seam 40c shown in FIG. 15, first and second opposed plies of fabric 42c, 44c being on opposite sides of the springs 18, a plurality of pockets 46c being formed along a length of said string 26c by transverse seams 48c joining said first and second plies, at least one spring 18 being positioned in each pocket 46c. Although one type of spring 18 is shown, any spring may be incorporated into any of the pockets 46c.

As best shown in FIG. 15A, each pocket 46c of pocketed spring assembly core 34c has an upper surface 68c and a lower surface 70c. As best shown in FIG. 15A, the upper surfaces 68c of the pockets 46c of pocketed spring assembly core 34c are generally co-planar in an upper plane P1 and the lower surfaces 70c of the strings 26c of pocketed spring assembly core 34c are generally co-planar in a lower plane P2. The linear distance between upper and lower surfaces 68c, 70c of the strings 26c of pocketed spring assembly core 34c is defined as the height "H" of the pocketed spring assembly core 34c because all the strings 26c are the same height.

As best shown in FIG. 15A, scrim sheet 36 is secured to an upper surface 68c of at least some of the strings 26c of pocketed spring assembly core 34c with beads 71 of adhesive/glue. Similarly, dimensionally stabilizing substrate 38 is secured to the lower surface 70c of at least some of the strings 26c of pocketed spring assembly core 34c with beads 73 of adhesive. Although not shown, the dimensionally stabilizing substrate 38 may be secured to the upper surface 68c of at least some of the strings 26c of pocketed spring assembly core 34c with adhesive and the scrim sheet 36 secured to the lower surface 70c of at least some of the strings 26c of pocketed spring assembly core 34c with adhesive. In some applications, the scrim sheet may be omitted.

15

Instead of beads, the adhesive securing the strings 26c of pocketed spring assembly core 34c to the scrim sheet 36 and to the dimensionally stabilizing substrate 38 may be lines or segments of glue.

As best shown in FIG. 15B, adjacent strings 26c are glued to each other with beads of adhesive 81. Instead of beads, the adhesive securing adjacent strings 26c of pocketed spring assembly core 34c may be lines or segments of glue. Although FIG. 14C shows three levels of glue beads 81, any number of levels of glue may be used to secure adjacent strings 26c together.

As best shown in FIGS. 15A and 15B, each string 26c has a continuous loop 85 of perforations 87 around the entire string. FIG. 15A shows one side section 89 of the loop 85 of perforations 87 extending through one of the plies 42c, 44c of the piece of fabric used to create the string 26c. FIG. 15B shows one end section 91 of each of the loops 85 of perforations 87 extending through the piece of fabric used to create each string 26b. The continuous loop 85 of perforations 87 extends around the entire string 26c facilitating the tearing of the fabric as described herein.

The pocketed spring assembly 12c has a first continuous loop 85 of perforations 87 proximate the dimensionally stabilizing substrate 38 in the lower third of the pocketed spring assembly 12c. The pocketed spring assembly 12c also has a second continuous loop 15 of perforations 17 proximate the scrim sheet 36 in the upper third of the pocketed spring assembly 12c.

As shown in FIG. 15C, due to the presence of two continuous loops 85, 15 of perforations around each string 26c, the metal of the spring assembly may be separated from the fabric of the spring assembly for recycling purposes quickly and easily. A person or a machine grabs the scrim sheet 36 and the dimensionally stabilizing substrate 38 and pulls them apart or away from each other in the direction of arrows 111 shown in FIG. 5C. The fabric of the pockets 46c of strings 26c open by the fabric tearing along the perforations. The perforations 87, 17 are the weak links in the fabric and thus open first. The coil springs 18 may be removed from inside the pockets 46c either by gravity or machine or manually. See arrow 109 of FIG. 15C.

After the metal coil springs 12 have been separated from the fabric by tearing along the perforations 87, 17, the fabric of the pocketed spring assembly 12b is separated into a first or lower section of fabric 113 having the dimensionally stabilizing substrate 38, a second or upper section of fabric 115 having the scrim sheet 36 and a third or middle section of fabric 117.

To ease the recycling at the end of life of a bedding or seating product, such as a mattress, the adhesive may be made of polypropylene, the fabric of the scrim sheet may be made of polypropylene, the fabric of the dimensionally stabilizing substrate may be made of polypropylene and the fabric used to create the strings may be made of polypropylene. Thus, after the separation of the metal of the pocketed spring assembly from the fabric, all of the fabric is may be made of polypropylene and may be quickly and easily recycled.

Tearing is possible because the tensile strength of the pieces of fabric of the strings 26c is less than the tensile strength of the dimensionally stabilizing substrate 38. In some applications, the tensile strength of the dimensionally stabilizing substrate 38 is at least twice as great as the tensile strength of the pieces of fabric of the strings 26c.

The various embodiments of the invention shown and described are merely for illustrative purposes only, as the drawings and the description are not intended to restrict or

16

limit in any way the scope of the claims. Those skilled in the art will appreciate various changes, modifications, and improvements which can be made to the invention without departing from the spirit or scope thereof. The invention in its broader aspects is therefore not limited to the specific details and representative apparatus and methods shown and described. Departures may therefore be made from such details without departing from the spirit or scope of the general inventive concept. The invention resides in each individual feature described herein, alone, and in all combinations of any and all of those features. Accordingly, the scope of the invention shall be limited only by the following claims and their equivalents.

What is claimed is:

1. A method of disassembling a pocketed spring assembly, the method comprising:

providing a pocketed spring assembly having a dimensionally stabilizing substrate secured to one of top and bottom surfaces of the pocketed spring assembly and a scrim sheet secured to the other of the top and bottom surfaces of the pocketed spring assembly, said pocketed spring assembly comprises a plurality of parallel strings of springs joined together, each of said strings comprising a plurality of individually pocketed springs, each of said strings comprising a piece of fabric joined along a longitudinal seam, first and second opposed plies of fabric being on opposite sides of the springs, a plurality of pockets being formed along a length of said string by transverse seams joining said first and second plies, at least one spring being positioned in each said pockets, said dimensionally stabilizing substrate being thicker than the scrim sheet and more rigid than the scrim sheet; and

pulling the dimensionally stabilizing substrate and the scrim sheet away from each other to tear the strings along perforations in the piece of fabric.

2. A method of claim 1, further comprising removing the springs from the piece of fabric.

3. A method of claim 1, wherein said dimensionally stabilizing substrate comprises a sheet at least twice as thick as the scrim sheet to facilitate gripping the dimensionally stabilizing substrate.

4. The method of claim 1 wherein said dimensionally stabilizing substrate has a weight of at least two ounces per square.

5. The method of claim 1, wherein tearing the strings along perforations in the piece of fabric is facilitated by each of the strings having perforations fully around the string.

6. The method of claim 1 wherein the perforations are closer to the dimensionally stabilizing substrate than to the scrim sheet to facilitate tearing the strings.

7. The method of claim 1 wherein tearing the strings along perforations in the piece of fabric avoids tearing the transverse seams of the pocketed spring assembly.

8. A method of disassembling a pocketed spring assembly, the method comprising:

providing a pocketed spring assembly having a dimensionally stabilizing substrate secured to one of top and bottom surfaces of the pocketed spring assembly and a scrim sheet secured to the other of the top and bottom surfaces of the pocketed spring assembly, said pocketed spring assembly comprises a plurality of parallel strings of springs joined together, each of said strings comprising a plurality of individually pocketed springs, each of said strings comprising a piece of fabric joined along a longitudinal seam, first and second opposed plies of fabric being on opposite sides of the springs, a

17

plurality of pockets being formed along a length of said string by transverse seams joining said first and second plies, at least one spring being positioned in each said pockets, said dimensionally stabilizing substrate being thicker than the scrim sheet and more rigid than the 5 scrim sheet; and

tearing each of the strings along perforations in the piece of fabric to separate the springs from the fabric.

9. The method of claim 8, wherein tearing each of the strings along perforations in the piece of fabric separates the 10 spring assembly into two sections of fabric.

10. The method of claim 9, wherein one of the sections of fabric has the dimensionally stabilizing substrate and the other section of fabric has the scrim sheet.

11. The method of claim 8, wherein tearing each of the strings along perforations in the piece of fabric comprises 15 pulling apart the dimensionally stabilizing substrate and the scrim sheet.

12. The method of claim 8, wherein tearing each of the strings along perforations in the piece of fabric comprises 20 using the dimensionally stabilizing substrate and the scrim sheet as handles.

13. The method of claim 8, wherein the scrim sheet and the fabric of the strings are made of the same material to 25 facilitate recycling.

14. The method of claim 8, wherein said springs fall out of the pockets of the spring assembly after the strings are torn.

15. A method of disassembling a pocketed spring assembly, the method comprising:

providing a pocketed spring assembly having a dimensionally stabilizing substrate secured to one of top and bottom surfaces of the pocketed spring assembly and a

18

scrim sheet secured to the other of the top and bottom surfaces of the pocketed spring assembly, said pocketed spring assembly comprises a plurality of parallel strings of springs joined together, each of said strings comprising a plurality of individually pocketed springs, each of said strings comprising a piece of fabric joined along a longitudinal seam, first and second opposed plies of fabric being on opposite sides of the springs, a plurality of pockets being formed along a length of said string by transverse seams joining said first and second plies, at least one spring being positioned in each said pockets, said dimensionally stabilizing substrate being thicker than the scrim sheet and more rigid than the 5 scrim sheet;

grasping the dimensionally stabilizing substrate with one hand and the scrim sheet with the other hand; and tearing each of the strings along perforations in the piece of fabric to separate the springs from the fabric.

16. The method of claim 15, wherein the dimensionally stabilizing substrate is easier to grasp than the scrim sheet because it is thicker than the scrim sheet.

17. The method of claim 15, wherein said dimensionally stabilizing substrate is rectangular and extends outwardly from the strings.

18. The method of claim 15, wherein said scrim sheet is rectangular and extends outwardly from the strings.

19. The method of claim 15, wherein said perforations go around each of the strings.

20. The method of claim 15, wherein said springs fall out of the pockets of the spring assembly after the strings are torn.
